US0D1081915S

(12) **United States Design Patent** (10) **Patent No.:** **US D1,081,915 S**
(45) **Date of Patent:** **** Jul. 1, 2025**

(54) **WATER FILTER**

(71) Applicant: **Weibin Xu**, Yuyao (CN)

(72) Inventor: **Weibin Xu**, Yuyao (CN)

(73) Assignee: **Weibin Xu**, Yuyao (CN)

(**) Term: **15 Years**

(21) Appl. No.: **29/982,476**

(22) Filed: **Jan. 6, 2025**

(51) LOC (15) Cl. **23-01**

(52) U.S. Cl.

USPC **D23/209**

CLAIM

The ornamental design for water filter, as shown and described.

DESCRIPTION

FIG. 1 is a front perspective view of water filter, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

(Continued)

The broken lines in the drawings illustrate the portions of the water filter, which form no part of the claimed design.
